INVENTOR
GEORGE P. GAIL

BY *Frank C. Gail*

ATTORNEYS

UNITED STATES PATENT OFFICE.

GEORGE PHILIP GAIL, OF BALTIMORE, MARYLAND, ASSIGNOR TO THE GAIL MANUFACTURING COMPANY, OF BALTIMORE, MARYLAND, A CORPORATION OF MARYLAND.

PUNCH.

Application filed December 15, 1922. Serial No. 607,168.

To all whom it may concern:

Be it known that I, GEORGE P. GAIL, a citizen of the United States, and a resident of Baltimore, in the State of Maryland, have **5** invented a new and Improved Punch, of which the following is a full, clear, and exact description.

This invention has relation to a device for perforating sheet material and has reference **10** to a punch which is particularly designed for the purpose of perforating paper sheets for accurately fitting the retaining elements of a loose leaf binder.

One of the principal objects of the present **15** invention is to provide a device of the character described which facilitates the accurate spacing of the perforations in a sheet whereby the same will fit a loose leaf binder.

A further object of the invention lies in **20** the simplicity and cheapness of construction of the punch elements which involve a minimum number of manufacturing operations.

As a further object the invention contemplates a device for perforating a plurality **25** of openings in a sheet, which is capable of adjustment for spacing the perforations with respect to each other and relative to the margin of the sheet.

As a still further object the invention **30** contemplates a punch element which is provided with suitable means for stripping the sheets from the punch plug and which affords means for permitting of the clearing of the punchings therefrom.

The invention furthermore contemplates **35** a device for punching a plurality of apertures in a sheet which is so constructed as to permit of its association with a loose leaf binder without interfering with the opening or closing of the same.

With the above recited and other objects in view, the invention resides in the novel construction set forth in the following specification, particularly pointed out in the appended claims and illustrated in the accompanying drawing, it being understood that **45** the right is reserved to embodiments other than those actually illustrated herein to the full extent indicated by the general meaning of the terms in which the claims are expressed.

In the drawing—

Figure 1 is a plan view of a punching de-

vice constructed in accordance with the invention.

Fig. 2 is a transverse sectional view taken approximately on the line 2—2 of Fig. 1.

Fig. 3 is a sectional view taken approximately on the line 3—3 of Fig. 2.

Referring to the drawing by characters of reference 10 designates a flat strip of material provided with graduations 11 on its upper face adjacent one edge. A plurality of punch elements designated generally by the character 12 are associated therewith **60** and are adjusted relatively on the strip 10 to conform with the graduations thereon whereby to obtain a measured distance therebetween. The punch elements 12 are constructed from a single strip of resilient material which is bent upon itself to provide a pair of superposed leaves connected at one end. The lower leaf 13 is of slightly greater length than the upper leaf and constitutes a base which is provided **70** with an aperture 14 adjacent its free end to constitute a female die member. The side edges of the base are depressed or offset downwardly to provide a pair of parallel strengthening and supporting ribs 15 which **75** elevate the lower surface of the portion which lies therebetween above the supporting surface. The upper leaf is provided with a pair of U-shaped slits 16 and 17, the former slit defining a spring tongue 18 and **80** the latter an attaching lug 19 which is provided with an elongated opening 20, said lug being bent rearwardly and curved upwardly sufficient to raise it above the backbone of a ring binder to allow the base or lower leaf **85** 13 to rest flat when the binder is opened. The remaining uncut portion of the upper leaf which is substantially a U-shaped element 21 is spaced above and parallel to the lower leaf 13 for the major portion of its **90** length. Adjacent its free extremity the element 21 is offset downwardly as at 22 and is upturned slightly at its extreme free end as at 23 to afford an entering mouth 24 to facilitate the insertion of a sheet therebeneath **100** and between the same and the base or lower leaf 13 which extends slightly beyond the upturned extremity 23 to provide a shelf upon which the sheet is initially laid prior to its insertion. The side legs of the slit 16 **105** converge toward the bight portion of the

slit, thus forming the tongue 18 with complementary converging side edges from its connected end to its outer free end. Adjacent the connected end the spring tongue 18 is bent upwardly to provide a transverse beading 25 which, in addition to increasing the resiliency of the same, draws the tongue backwardly relative to the element 21 to allow for sufficient clearance between the same and the element 21 to permit of a free working of the tongue through the cutaway portion of the element 21. At the outer free end the tongue is provided with an aperture 26 in alignment with the aperture 14 of the base 13 and a punch plug 27 having a beveled lower end 28 and a headed upper end 29 is inserted through the aperture 26 and retained in a position by a forced fit with the head 29 overlying the upper surface of the tongue to provide a manipulating portion with which the thumb or finger engages. The tongue 18 is normally disposed at an inclination from its connected end to its free end whereby the lower end of the punch plug 27 will be normally elevated above the lower surface of the element 21 adjacent its free extremity. The element 21 constitutes a stripper to allow for the withdrawal of the punch plug from the sheet when pressure on the tongue is released and said element 21 in addition constitutes a clamp adjacent its connected end for associating the punch elements 12 with the strip or ruler 10.

In use and operation, when a sheet is inserted between the stripper 21 and the base 13 the tongue 18 is pressed down by the thumb or finger by pressure exerted on the head 29, thus causing the plug 27 to enter the aperture 14 and perforate the sheet. When the pressure is released the tongue 18, due to its inherent resiliency, springs back to its normal inclined position to withdraw the plug from the aperture 14 and the sheet. The sheet is prevented by the stripper member 21 from moving upwardly with the plug and is therefore stripped from the same. The punchings are allowed to fall through into the clearance space 30 defined between the under side of the base and the support. The strip or ruler 10 serves as a gage for the distance between the perforations in the sheet and the edge of the sheet, which distance may be varied by the width of strip or ruler 10 which is employed. Any number of punch elements 12 may be associated with the strip or ruler 10 or said punch elements may be individually used, the lugs 19 constituting means for associating the same with a key ring or watch chain.

I claim:

1. A punching device comprising a base having an apertured end, a leaf having a longitudinal slot connected to the non-apertured end of the base and overlying the

same in a substantially parallel plane thereto, a resilient arm connected to said non-apertured end of the base, normally projecting upwardly at an inclination thereto and movable through the slot in said leaf, a punch plug carried by the free end of said arm adapted upon depression of the arm, to cooperate with the aperture for perforating a sheet inserted between the leaf and the base, the said leaf constituting a stripper member adapted to strip the sheet from the punch plug upon upward movement of the arm therethrough.

2. A punching device comprising a base having an apertured end, a leaf having a longitudinal slot connected to the non-apertured end of the base and overlying the same in a substantially parallel plane thereto, a resilient arm connected to said non-apertured end of the base, normally projecting upwardly at an inclination thereto and movable through the slot in said leaf, a punch plug carried by the free end of said arm adapted upon depression of the arm, to cooperate with the aperture for perforating a sheet inserted between the leaf and the base, the said leaf constituting a stripper member adapted to strip the sheet from the punch plug upon upward movement of the arm therethrough, said arm being upwardly offset adjacent its connected end for receiving and embracing a graduated bar whereby the punching device is associated with the graduated bar, and whereby said bar when associated with the punching device serves as a stop with which the edges of the sheet are adapted to coat when inserted in the punching device.

3. A sheet punch consisting of a base having an apertured end constituting a female die member, a resilient leaf having a longitudinal slot connected to the non-apertured end of the base and overlying the same in a plane substantially parallel thereto, said leaf having its forward free end offset downwardly with its connected end vertically spaced from the base, a resilient arm connected to said non-apertured end of the base normally projecting upwardly at an inclination thereto and adapted for movement through the slot in said leaf upon depression of its free end, a plug carried by said free end of the arm constituting a male die member adapted upon depression of said arm to cooperate with the female die portion of the base to perforate a sheet inserted between the leaf and base, the said leaf constituting with the base a sheet clamping means, and said leaf further constituting a stripper member adapted upon an upward movement of the arm therethrough to strip the sheet from the punch plug.

4. A sheet punch consisting of a base having an apertured end constituting a female die member, a resilient leaf having a

longitudinal slot connected to the non-apertured end of the base and overlying the same in a plane substantially parallel thereto, said leaf having its forward free end offset downwardly with its connected end vertically spaced from the base, a resilient arm connected to said non-apertured end of the base normally projecting upwardly at an inclination thereto and adapted for movement through the slot in said leaf upon depression of its free end, a plug carried by said free end of the arm constituting a male die member adapted upon depression of said arm to cooperate with the female die portion of the base to perforate a sheet inserted between the leaf and base, the said leaf constituting with the base a sheet clamping means, and said leaf further constituting a stripper member adapted upon an upward movement of the arm therethrough to strip the sheet from the punch plug, the said base having downwardly offset longitudinal side portions constituting strengthening ribs and serving to space the lower face of the portion lying between said downwardly offset portions from the supporting surface to afford a clearance space for the punchings.

5. A sheet punch constructed from a single piece of resilient material bent upon itself to form superposed leaves connected at one end, the lower leaf having an aperture adjacent its free end and constituting a female die member, the upper leaf having a substantially U-shaped slit the bight of which is located adjacent the free end of said leaf, said slit dividing the upper leaf into a U-shaped arm which lies parallel to the lower leaf and constitutes a stripper member and into an arm disposed at a nor-

mal upward inclination, a plug carried by 40 said inclined arm and constituting therewith a depressible male die member adapted upon depression to cooperate with the apertured portion of the female die member to perforate a sheet inserted between the stripper member and the lower leaf and adapted to cooperate with said stripper member upon release of the male die member, to effect the stripping of the perforated sheet from the male die member. 45

6. A sheet punch constructed from a single piece of resilient material bent upon itself to form superposed leaves connected at one end, the lower leaf having an aperture adjacent its free end and constituting a female die member, the upper leaf having a substantially U-shaped slit the bight of which is located adjacent the free end of said leaf, said slit dividing the upper leaf into a U-shaped arm which lies parallel to the lower leaf and constitutes a stripper member and into an arm disposed at a normal upward inclination, a plug carried by 50 said inclined arm and constituting therewith a depressible male die member adapted upon depression to cooperate with the apertured portion of the female die member to perforate a sheet inserted between the stripper member and the lower leaf and adapted to cooperate with said stripper member upon release of the male die member, to effect the stripping of the perforated sheet from the male die member. 55

6. A sheet punch constructed from a single piece of resilient material bent upon itself to form superposed leaves connected at one end, the lower leaf having an aperture adjacent its free end and constituting a female die member, the upper leaf having a substantially U-shaped slit the bight of which is located adjacent the free end of said leaf, said slit dividing the upper leaf into a U-shaped arm which lies parallel to the lower leaf and constitutes a stripper member and into an arm disposed at a normal upward inclination, a plug carried by 60 said inclined arm and constituting therewith a depressible male die member adapted upon depression to cooperate with the apertured portion of the female die member to perforate a sheet inserted between the stripper member and the lower leaf and adapted to cooperate with said stripper member upon release of the male die member, to effect the stripping of the perforated sheet from the male die member, and an apertured lug cut from the spring tongue and bent in an opposite direction thereto to provide an attaching means for associating the device with another article. 65
